CIGARETTE LIGHTER

Seymour Rappoport, Rumson, N.J., assignor to Ronson Corporation, Woodbridge, N.J., a corporation of New Jersey

Filed Sept. 8, 1966, Ser. No. 3,780

Term of patent 14 years

(Cl. D48—27)

FIG. 1 shows a perspective view of a cigarette lighter embodying my new design.

FIG. 2 shows a perspective view showing the base portion partially cut away.

FIG. 3 is a perspective view showing the upper portion of the cigarette lighter separated from the base.

I claim:

The ornamental design for a cigarette lighter, substantially as shown and described.
